CIGAR VENDING APPARATUS

Martin M. Berger and John Morales,
New York, N. Y.

Application September 4, 1946, Serial No. 694,774

2 Claims. (Cl. 312—46)

1

The invention relates to apparatus for vending cigars.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a fragmentary side elevation, with parts in section, of a cigar vending magazine in a machine embodying the invention;

Fig. 2 is a vertical section on line 2—2 of Fig. 1;

Fig. 3 is a fragmentary side elevation of the mechanism shown in Fig. 1 viewed from the opposite side;

Fig. 4 is a series of four operational views taken in section on lines A—A, B—B, C—C and D—D of Fig. 3; and showing different operational positions of the mechanisms;

Fig. 5 is a horizontal section taken on line 5—5 of Fig. 3;

Fig. 6 is a vertical section taken on line 6—6 of Fig. 3;

Fig. 7 is an enlarged fragmentary vertical section of the cigar ejecting means of the mechanism shown in Fig. 2;

Fig. 8 is a reduced front elevation of the complete vending machine embodying the invention;

Fig. 9 is an elevation of the cardboard blank forming the cigar holding carton;

Fig. 10 is a perspective of the carton formed from the blank shown in Fig. 9, shown in partially opened position;

Fig. 11 is a similar perspective of said carton shown in closed and sealed position;

Fig. 12 is a vertical section on line 12—12 of Fig. 11; and

Fig. 13 is a perspective of the same carton, with certain elements thereof torn away in accordance with the invention.

Objects of the invention are to provide a novel and useful machine for vending cigars quickly, efficiently, inexpensively and without injury to the vended articles. Another object is to provide such a machine in which the container for supplying cigars to the machine remains in place in

2

the machine and constitutes an operative element in combination with the vending mechanism to facilitate the vending of the cigars and other operations of the machine. Another object of the invention of the machine is to provide a novel and useful form of container and carton for carrying and loading cigars into a vending machine and for cooperating with the vending mechanism.

In cigar vending machines heretofore it has been necessary to provide means for accommodating the cigar-holding and feeding or vending devices to different sizes and shapes of cigars. Such means have been regarded as necessary because of the relatively great variation in the sizes and shapes of commercially available cigars and the impracticability of designing and building separate vending machines for vending each such size and shape of vended product. However, in practice it has been found that the means of adjustment heretofore provided for such purposes are not wholly satisfactory principally because they require frequent settings by servicemen to adapt the vending mechanism to changes in the brands or sizes and shapes of cigars supplied to the machine. Such service adjustments are frequently made carelessly by unskilled help so as to render the machine inoperative or to cause damage to the cigars being vended.

Consequently one primary object of the invention is to provide a cigar vending and ejecting mechanism which will feed all sizes and shapes of cigars freely, safely and accurately from the container or magazine holding them without requiring any service adjustments or settings. The machine of our invention will handle all sizes and shapes of cigars indiscriminately and will facilitate the feeding movement of cigars lying in column in the supply magazine so as to avoid any jamming or dislodgment thereof which would interfere with the vending action. The vending means of the present invention automatically adapts itself to any sizes or shapes of cigars. It also prevents more than one cigar from being fed at a time and is so designed as to retain control over the movement of the cigar being fed and of the stack of cigars in the magazine column above it until the final moment of ejection.

We have also found in machines heretofore designed for feeding cigars which are loaded or fed into a vertical column magazine by means of an insertable carton or container, that such cartons introduce drawbacks into the operation and servicing of the vending machine. For example, with such cartons it has heretofore been

difficult for the serviceman to tell readily how many cigars remain in any magazine. Moreover cartons which properly house cigars in shipment usually provide a rather tight fit for the cigars within them so that the cigars when positioned in the vending machine magazine and still within the carton do not feed readily therefrom. Also, such cartons normally provide no convenient way to load a few individual cigars into a partially depleted carton in a magazine without either removing the carton from the magazine or forcing cigars into the open top of the carton and thereby frequently causing injury to the cigars or jamming or other irregularity in their stacking.

Other objects of the invention therefore comprise providing a novel cigar-containing and loading carton which will avoid the above-mentioned drawbacks. The carton of our invention makes the cigars in the entire stack within a magazine viewable and accessible to the serviceman at all times. The carton construction also enhances free flow of the cigars for feeding and delivery from the vertical stack thereof. It also facilitates partial or complete reloading at any time while the carton is in the magazine. The novel carton of our invention is also designed to cooperate mechanically with the vending mechanism, providing a clearance space for action of means operable when the carton has been emptied to indicate the absence of cigars and to prevent operation of that particular vending mechanism until its magazine has been replenished with one or more cigars. Thus both the construction of the carton itself and the combination of the carton structure with operating parts of the vending mechanism are novel and useful features of our invention.

It will be understood that the foregoing general description and the following detailed description as well are exemplary and explanatory but are not restrictive of the invention.

Referring now in detail to the present preferred embodiment of the invention which is illustrated by way of example in the accompanying drawings, a general showing of such vending machine is to be found in Fig. 8. Said machine preferably comprises a vertically disposed outer rectangular metal casing 1 which may be suspended against any suitable vertical surface such as a wall or pillar or may rest upon a suitable base 2. The front wall of the casing 1 is preferably provided with a window 3 which may be glass sealed and bear on a part of its surface pictures or models or other indicia for representing the types of cigars contained in the various vending magazines within the machine. As shown, the machine is designed for five magazines containing five vertical columns of cigars and the corresponding indicia 4 so indicate five cigars of various types, sizes, shapes and prices. It will be understood, however, that the invention is not limited to any particular number or arrangement in these respects.

As viewed from the front, the machine is provided with five knobs 5 formed at the ends of coin-controlled actuating rods 25 for the several vending magazines. Above each knob the front panel of the machine is provided with a corresponding small opening or window 6 for observation of the indicator showing whether or not the particular magazine is empty. Below the row of knobs 5 there is provided an opening 7 through which the customer may withdraw a cigar delivered by one of the vending magazines into the common hopper or chute communicating with

said opening 7. It will be understood that for the most part the mechanism hereinabove described is generally conventional in form and construction and that the invention will admit of substantial modifications and variations therefrom.

Referring now to the internal construction of the vending machine which relates particularly to the cigar-holding magazines and delivery mechanism therefor, the general arrangement thereof is shown in Figs. 1 to 3 and 5. As embodied, the main casing 1 is formed about a rectangular supporting shelf 10 having flanged vertical front wall 11, rear wall 12 and side walls 13. Said shelf comprises a horizontal base or support for the vertical magazines which rest thereupon. The magazines themselves comprise narrow rectangular boxes or casings having flat vertical side walls 15 and 16, front and rear end walls 17 and 18, respectively, rectangular bottom plate 19 and an open top.

For convenience in installing and removing said magazines, they are preferably removably and slidably supported with respect to the platform 10. For this purpose, channels 20 are fixed to the upper surface of platform 10 while corresponding T-shaped tongues 21 are fixed to the bases 19 of the magazines, as shown in Fig. 7, for example.

It will be understood that the magazines are normally seated in the channels 20 and that the supplies of cigars are furnished to the magazines by insertion of loaded cartons A generally shown in Figs. 11 and 12, said cartons being of a size and shape to hold a vertical stack of superposed cigars C lying with their longer axes horizontal. The detailed construction and the cooperation of said cartons with the magazines will be later described in detail. In accordance with the invention each cigar vending magazine is associated with actuating mechanism for effecting the operation of delivery means for vending the cigars therefrom. Such actuating means comprises primarily, as to each magazine, a horizontally-disposed actuator rod 25 which projects forwardly from the face of the cabinet 1 and on the forward end of which is mounted a knob 5. Said actuator rods 25 extend through the front wall of the casing 1 and front wall 11 of the platform 10, running beneath and parallel to said platform to project through an opening in the rear platform wall 12. Each of said rods is normally maintained in the forwardly projecting position by means of a coil spring 26, one end of which is fixed to the rod at 27 and the other end to the bottom of the platform 10 at 28. The rod 25 is designed, by means of a mechanism later to be described, to release and expel one cigar from the bottom of its corresponding magazine when pushed in by the customer and released to return under the tension of the spring 26. This vending movement of the push rods 25 is subject to a coin control, the details of which are not shown but the general principles of which will be understood by those skilled in the art.

Each of the cigar magazines is designed to release a cigar upon operation of the corresponding push rod 25 and the features of that means for feeding and controlling the feed of the cigar from the bottom of the vertical stack thereof within a carton lined magazine comprise one of the important features of the invention. This mechanism is shown in detail in Figs. 2, 5, 6 and 7 and comprises fundamentally means for positioning the cigar at the bottom of the stack between two resilient gripping members or surfaces 75 which exert and retain a light resilient grip on

the cigar, preferably throughout most of its length, as it is being ejected from the bottom of the stack in the magazine. As shown in Fig. 7, a cigar C (shown as the last cigar in the magazine for the sake of clearness) is being ejected from the bottom 19 thereof and into a receiving opening 30 formed in the floor plate 10. Thence the cigar will fall into the common delivery chute or hopper where it is accessible to the customer through the delivery opening 7.

In the preferred construction the stack of cigars C (Fig. 2) normally lie with the bottom cigar supported a substantial distance above the bottom plate 19 of the magazine by means of a movable ejector plate 31 which underlies the stack of cigars and normally lies parallel to and above the bottom 19 so as to constitute a movable or false bottom for the magazine. Said ejector plate 31 is preferably provided with a depending flange or lip 32 which, in the final position of the cigar in the magazine as shown in Fig. 7, serves as a bearing and pushing surface against the cigar. The ejector plate 31 is movably mounted so that it may be withdrawn from the bottom of the stack of cigars C to permit the lowermost cigar to fall into the ejecting position of Fig. 7, there to lie against the lip 32 after it has fallen or rolled off the supporting plate 31. While various means may be provided for effecting the resilient withdrawing and ejecting motions of plate 31, in the preferred embodiment this motion is accomplished by a pivotal connection between plate 31 and the left side wall 16 of the magazine. As shown in Figs. 2, 3 and 7, the left hand edge of plate 31 is formed as a flange on the upstanding normally vertical hinge plate 33 which normally lies against the wall 16 of the magazine and is pivotally connected thereto by horizontal hinge 34 (Fig. 3). An elongated leaf spring 35 has its lower free end 36 bearing against outer lower surface of plate 33, the upper end of said hinge being fixed to the wall 16 of the cabinet by the bracket 37. Thus the hinge normally urges the hinge plate 33 and the ejector plate 31 toward wall 16 so that the latter underlies the stack of cigars but may be withdrawn outwardly (to the left in Fig. 7) to permit the stack of cigars to fall and the lowermost cigar to rest on the true bottom plate 19 of the magazine as shown in Figs. 4-D and 7. The full extent of the outward movement of plates 33 and 31 is shown in said Fig. 4-D.

In accordance with the invention means are provided for cooperating with the resilient cigar ejecting motion of plate 31 so as to provide a cushioned or resilient grip and control on the ejecting movement of the cigar previously referred to. In the preferred embodiment, this means comprises a depending, normally vertical leaf 40, the lower edge of which is slightly curved outwardly at 41 to lie against the side of the cigar as it moves downwardly in the magazine and is then forced over the bottom 19 and out into the chute 30. The upper edge of said leaf 40 is pivotally associated with the vertical side wall 15 of the magazine, being mounted to turn with a horizontal cross rod 42. For this purpose the upper portion of leaf 40 is reduced in width and provided with struck-up ears 43 which are apertured to receive the shaft 42, which is fixed to turn with said plate 40. The shaft extends beyond the ears 43 to be journaled in suitable openings formed in lugs 45 and 46 upstanding from the face of wall 15 as shown in Fig. 1. A coil spring 47 is wound about a projecting end of the rod 42, one end of the spring bearing

against the face 15 of the magazine and the other end bearing against the outer face of leaf 40, thereby to impart a light resilient urge forcing said plate toward the interior of the magazine and against the cigars C. It will be noted that the magazine wall plate 15 is cut away entirely beginning a short distance below the line of shaft 42 to provide clearance down to the bottom plate 19 of the magazine. The leaf 40 is designed substantially to cover this gap by stopping short of the bottom 19, a distance equal to about the radius of an average size cigar. Preferably also the leaf 40 is cut away near its ends except for relatively narrow tongues 48 which extend across to lie against the vertical edges of the end walls of the magazine. Similarly to wall 15, the opposite wall 16 of the magazine is cut away at 49 for substantially the same distance from the bottom to provide room for the plate 31 to move into and out of its operating space. The magazine bottom plate 19 is curved upwardly a slight amount to provide a lip 50 guarding against rolling of cigars out of the magazine in the wrong direction.

The invention provides means for indicating when the supply of cigars in a particular magazine has been completely depleted and said means also acts to prevent actuation of the corresponding push rod 25 until the magazine has been replenished. For this purpose a normally elevated plate 55 is hung at the end of a pivoted bar 56, said bar being mounted intermediate its ends to rock about a pivot pin 57 projecting from the face of magazine wall 16. The plate 55 is provided with a sign marked "Empty" which, in the elevated position of said plate cannot be seen by the customer but, when the plate is lowered by the downward rocking of the right hand end of the bar 56 said "Empty" sign comes into view through the opening 6. The lower end of said plate 55 comprises a narrow prolonged detent tongue 58 adapted to move through an opening 59 in the floor plate 10, and, in the lower position, to engage a notch 60 in the upper face of push rod 25. Thus when the plate 55 is lowered, the "Empty" sign will come into view and the customer will be prevented from actuating the push rod 25. The tendency of bar 56 is to tilt into the "Empty" and locking position.

Means are provided for holding the plate 55 and its associated lever bar 56 in the elevated position so long as there are any cigars C in the magazine. Such means comprise a finger or feeler 65 pivotally mounted at 66 on a channel bracket 67 extending from the wall 16 of the magazine. Said finger 65 normally is depressed by the presence of cigars C in the magazine as shown in Figs. 2 and 4-D. The lower or outer side of said finger 65 is cut away to form a curved notch or hook at 68 and said hook normally engages and lies against a rounded member 69 formed on the depressed end of pivot bar 56. When in that position, as shown in Figs. 2 and 4-D, the depressed hook 65 prevents the bar 56 from tilting under the weight of plate 55. However, when the magazine becomes emptied of cigars the finger 65 is free to move inwardly and upwardly into the magazine and thus permits the bar 56 to tilt about its pivot to lower plate 55.

It will be noted that the hinge plate 33 is cut away at 70 to accommodate bracket 67, finger 65 and their associated parts, and said hinge plate is also provided with a U-shaped channel 71 which provides clearance for the

pivot pin 57 and the bar 56. In accordance with the invention means are provided for causing the movement of push rod 25 to rock the hinge plate 33 outwardly so as to draw the ejector plate 31 from beneath the stack of cigars and then to permit return of said plate to eject a cigar as previously described. For this purpose the inner end of push rod 25 is designed to engage movably a bell crank 75 by means of a roller 76 at the end of the rod. The fixed pivot 71 of said bell crank is connected by a pivot pin to rear wall 78 of the casing structure, while the intermediate pivot 79 of the bell crank is journaled in the lower end of pivoted channel 80. The upper end of said channel is pivotally connected at 81 to the top of a vertically slidably frame 82. Rearward motion of the actuator bar 25 thus rocks the bell crank and causes channel 80 to slide the frame 82 upwardly. The frame 82 is mounted for vertical sliding movement with respect to vertical plate 78 which is fixed to and projects upwardly from the rear wall 12 of the casing base plate 10. For this purpose the frame 82 is provided with two staggered vertical slots 84 and 85 and cooperating with guide bolts and washers 86 which are fastened to the vertical plate 78. Thus the frame 82 has limited vertical sliding movement with respect to said plate 78.

Means are provided for causing the vertical upward movement of said frame 82 to rock the hinge plate 33 outwardly as previously described. For this purpose a rod 90 is fixed to and projects from the rear face 91 of the hinge plate 33 and said rod is provided at its rear end with a roller 92. Said roller projects through an opening 93 in the wall 78 and is received in an inclined channel or guide slot 95 formed in the vertical frame 82. As will be clear from Figs. 4-A, B, C and D, the raising of frame 82 causes the roller 92 to be forced laterally (to the right in Fig. 4) thereby opening the hinge plate 33. When this movement is completed by the inward movement of the push rod, release of the push rod will cause the frame 82 to fall, restoring the parts to their previous positions and thereby ejecting the cigar as indicated in Fig. 7.

It will be understood that the cigar ejecting mechanism herein shown and described is designed to accommodate itself to different sizes and shapes of cigars without requiring any change or setting of the mechanism, because of the resilient contact of the gripping surface against the cigar. The resilient leaf 40 also serves to prevent more than one cigar being fed at a time as it tends to hold back upper cigars from following the one being fed. The movable bottom plate 31 and leaf 40 also prevent jamming or crushing of cigars because said members engage substantially throughout the cigar length and thus automatically cause them to straighten out and lie flat before they can be ejected.

Referring now to the novel construction of the carton A and its mechanical cooperation with the cigar-dispensing mechanism, said carton is designed to completely enclose the cigar in a package sealed with the revenue stamp S prior to introduction of the loaded carton into the machine. The carton blank is shown in Fig. 9 and comprises the solid vertical face 100 with the top flap 101 creased at 102 and 103. Locking slot 104 is provided at the center of the top flap 101. Along its left-hand edge the wall 100 is creased at 105 and the extending flap 106 is also centrally creased at 107 to provide the ver-

tical edge fold as shown in Fig. 10. The opposite side of the blank is creased at 108 and again at 109 to form the opposite corresponding vertical edge of the carton while the portions 110 and 111 extending therebeyond comprise the opposite face or front of the carton. Tongue 112 is formed at the top edge of sheet 111 to cooperate with slot 104 while a bottom tongue 113 similarly cooperates with a slot 114 in the bottom flap 115. Said bottom flap is also centrally creased at 116 to form the upturned bottom flange as shown. The blank as shown and described is assembled in closed form as shown in Figs. 11 and 12, being thus loaded with cigars and adapted to be introduced into the machine magazine within which it snugly fits.

In accordance with the invention certain parts of the carton are adapted to be removed at the time of insertion into the machine so as thereafter to facilitate freedom of movement of the cigars and inspection or examination of the magazine contents. For this purpose the flap 111 is joined to section 110 by a perforated line 120 so that the flap 111 can be torn away as the carton is inserted into the machine as indicated in Fig. 13 and positionally shown in Figs. 1 and 5. In this case it will be noted that the side plate 15 of the magazine is cut away throughout its length to provide a vertical window equal to the width of the removed flap 111.

A bottom portion of the carton comprising slotted flap 115 is also adapted to be removed from the carton by means of perforated line 121. Also a tongue 122 is formed on the bottom flap 115, normally comprising a portion of the back wall 100 but being perforated so that when the bottom flap 115 is removed, said tongue 122 will come with it leaving an opening 123 at the bottom of wall 100. These portions of the carton are removed first before it is slid into the top of the magazine so that the cigars will be free to feed out of the bottom of the carton. It will be noted that the opening 123 formed in the wall 100 provides clearance for the movement of the feeler 65 with respect to the carton and cigars.

When the carton is inserted into the magazine it is designed to be held in proper spaced relation above the bottom of the magazine. For this purpose the top flap 101 is designed to be bent back over the top of wall 16 of the magazine and along the outside of said wall. The lower end of said flap is adapted to be caught in and supported by an outwardly turned tongue 125 formed for that purpose in the wall 16 (Fig. 2).

The invention in its broader aspects is not limited to the specific mechanisms shown and described but departures may be made therefrom within the scope of the accompanying claims without departing from the principles of the invention and without sacrificing its chief advantages.

What is claimed is:

1. A cigar vending machine including in combination a magazine for holding an upright stack of cigars superposed on each other and lying horizontal on their long axes, and means for feeding the bottom cigar from the stack comprising an ejection member completely underlying and supporting the bottom cigar along its long axis thereof, means for rearwardly withdrawing the ejection member from beneath the cigar causing it to fall downwardly into ejecting position, spring urged means for moving said ejection member forwardly to its original position to eject the fallen cigar laterally along its

long axis, and a gate member positioned opposite said ejection member and spring urged to engage the opposite side of the fallen cigar along its long axis to resiliently oppose the ejecting movement of said ejection member whereby the cigar is gripped along its long axis on opposite sides as it is being ejected.

2. A cigar vending machine including in combination a magazine for holding an upright stack of cigars superposed on each other and lying horizontal on their long axes, and means for feeding the bottom cigar from the stack comprising an ejection member, having a downwardly turned flange, completely underlying and supporting the bottom cigar along its long axis and normally holding the entire stack of cigars above the bottom of the magazine, means for rearwardly withdrawing the ejection member from beneath the stack of cigars causing the bottom cigar to fall downwardly to the bottom of the magazine into ejecting position, spring urged means for moving said ejection member forwardly to its original position to eject the fallen cigar laterally along its long axis by having the said flange portion come into contact with said cigar, and a gate member positioned opposite said ejection member and spring urged to engage the opposite side of the fallen cigar along its long axis to resiliently oppose the ejecting move-

ment of said ejection member whereby the cigar is gripped along its long axis on opposite sides as it is being ejected.
